UNITED STATES PATENT OFFICE.

WILLIAM S. RALYA, OF CINCINNATI, OHIO, ASSIGNOR TO ARTHUR H. BOHNSTENGEL,
OF CINCINNATI, OHIO.

FURNACE.

1,271,364.

Specification of Letters Patent.

Patented July 2, 1918.

Application filed December 9, 1915. Serial No. 65,915.

To all whom it may concern:

Be it known that I, WILLIAM S. RALYA, a citizen of the United States, residing at Cincinnati, in the county of Hamilton and State of Ohio, have invented certain new and useful Improvements in Furnaces, of which the following is a specification.

My invention relates to furnaces for melting, heating and reheating metals, and has 10 for its object the provision of a furnace so arranged as to provide a substantially equal temperature throughout the heating or melting chamber; further, to provide such furnace with valves of novel arrangement for 15 providing a desired mixture of fluid-fuel and air for obtaining the desired starting heat and for adjusting the positions of the mixers, whereby to increase the air or oxygen contents of the mixture for producing 20 combustion at high degrees of heat; and, further, to so control the currents of the products of combustion as to obtain substantially uniform heat throughout the heating chamber and great economy in the consumption of fuel.

The invention will be further readily understood from the following description and claims, and from the drawings, in which latter:

30 Figure 1 is an end elevation of my improved device.

Fig. 2 is a cross-section of the same taken on the line 2—2 of Fig. 3.

35 Fig. 3 is a horizontal plan section taken on the irregular line 3—3 of Fig. 1.

Fig. 4 is a horizontal plan section taken on a line corresponding to the line 4—4 of Fig. 2.

40 Fig. 5 is a vertical section taken on the line 5—5 of Fig. 1.

Fig. 6 is a detail in section taken on the line 6—6 of Fig. 1, showing the means for securing the upright fuel pipes in position.

45 Fig. 7 is a rear view of the same; and, Fig. 8 is an enlarged cross-sectional detail of the fuel valve mechanism taken on the line 8—8 of Fig. 3.

11 and 12 represent respectively the front and rear walls of the furnace, and 13 the 50 end walls thereof, 14 represents the arched top having an arched inner face, between which and a horizontal partition 15 the heating chamber 16 is located. The horizontal partition 15 forms the floor of the heating 55 chamber. Gas mixers are shown at 17 for

mixing fluid-fuel, for instance gas, from pipes 18, in which latter valves 19 are located for regulating the flow of gas, the gas being mixed with the air in the mixing funnel 20. A regulating disk 21 is provided 60 for regulating the percentage of air mixed with the gas, for accomplishing which there is a threaded connection 22 between the regulating disk and the gas-pipe.

The mixers are mounted on slides 26 slide- 65 able back and forth in suitable guideways 27 for regulating the distance between the discharging ends of the mixers and the inlet-passages 28 in the front wall of the furnace, for increasing the air-contents of the 70 mixture.

The pipes 18 have flexible connections with the supply-pipes 29 for the gas, as by means of the pipes 30, 31, connected together by the flexible joint 32 and connect- 75 ed with the pipes 29 and 18 by means of the flexible joints 33, 34. The guideways 27 form channels in which the slides 26 supporting the mixers are mounted, the slides being arranged to be moved manually along 80 the guideways, the weights of the slides and parts mounted thereon maintaining the same in adjusted positions. The slides may be independently moved and the valves independently regulated or employed, as desired. 85

The inlet-passages 28 are in line with the mixers for receiving the fuel discharged from the latter, the adjustment of the mixers and the distances of the mixers from the outer ends of the passages determining the 90 proportions of air mixed with the fluid-fuel.

A deflecting wall 36 is provided between the arch of the top and the floor of the heating chamber, and is preferably arranged at 95 an inclination up and down to correspond substantially to the general direction in which the lower end of the fuel-entering side of the arch extends. The deflecting wall forms a deflecting chamber 37 which ex- 100 tends preferably throughout the length of the furnace and opens upwardly. The speed of passage of the fluid-fuel is momentarily checked in the deflecting chamber for permitting the proper ignition of 105 the fuel.

The fuel strikes the wall 36, which deflects the fuel laterally so as to distribute the same lengthwise of the furnace, and also upwardly to induce a direction of movement 110

along the curvature of the bottom of the upper arched wall 14, as indicated by the arrows in Fig. 2, to downwardly opening passages 40 in the rear of the floor 15 at the 5 respective ends of the furnace, the downwardly opening passages 40 being separated by the integral portion 41 of the floor 15.

This construction causes the fuel and products of combustion to spread at their points of entrance throughout the length of the heating chamber and to move upwardly across the arched surface of the top, and at the rear of the latter to pass downwardly 10 through the passages 40 causing the fuel and products of combustion to spread throughout the area of the upper chamber 16, so that said chamber is heated equally throughout.

20 A lower chamber 42 is located under the floor 15 which forms the top of said chamber. Partitions 43 extend forwardly from the rear wall 12 in the lower chamber toward the front wall 11, between which and the 25 forward ends of said partitions passages 44 are located, the partitions forming end channels 45 and a middle channel 46 extending crosswise of the arched top under the floor.

The products of combustion pass through 30 the passages 40, the end-channels 45, the passages 44, about the partitions 43, and through the middle channel 46, in the rear end of which an opening 47 is located, communicating with a flue 48, the products of combustion 35 passing through said opening and flue. The flue preferably extends upwardly above the height of the furnace. The course of the passage of the products of combustion is indicated by the arrows in Figs. 2, 3 and 4.

40 The ends of the heating chamber are arranged to be closed by doors 51, which are movable in guides 52 and counterweighted by weights 53 connected with the door by cables 54 passing over sheaves 55 journaled 45 on pins 56 suitably secured to the framing 57 of the furnace. The framing of the furnace is instanced as built up with angle irons suitably bolted or riveted together.

My improved furnace is applicable for 50 melting metal placed in the furnace, for instance, in crucibles on the melting floor; also for heating metals, for instance for drawing out the tempers of saw-blades and other articles to which it is necessary to apply 55 an even temperature throughout the article, which is sometimes of considerable superficial area. The extreme range of heat regulation possible by my improved device is especially useful for purposes of this nature and also provides means whereby extremely high temperatures may be applied 60 for melting metals quickly.

When beginning the firing in my improved furnace, the gas mixers are preferably 65 placed adjacent to the outer ends of the in-

let-passages 28, whereby a limited amount of air is permitted to mix with the fluid-fuel, such as gas or oil. When beginning the firing, the regulation of the mixture is preferably obtained through the regulating disk 70 21, or a slight extent of separation between the ends of the mixers and the outer ends of the inlet-passages. This relation permits the proper ignition and burning of the mixed fuel in the heating chamber of the 75 furnace.

As the furnace becomes hotter, the mixers are adjusted away from the entering orifices of the inlet-passages, thereby permitting a greater quantity of air to pass between the 80 ends of the mixers and the inlet-passages, for causing a mingling of a greater amount of air with the fluid-fuel and a greater intensity of heat in the heating chamber. This heating, regardless of its intensity is at all 85 times uniform throughout the heating chamber, and the regulation of its intensity permits either an annealing heat or a melting heat to be obtained as may be desired.

My improved device provides great draft 90 of fuel into the heating chamber whereby larger proportions of air are drawn into the heating chamber for providing intense heat and economy of fuel.

Having thus fully described my invention, 95 what I claim as new and desire to secure by Letters Patent, is:

1. A furnace of the character described comprising a heating chamber having an arched top and a floor, a chamber under said floor, partitions dividing said last-named chamber into end channels and a middle channel the tops of which are formed by said floor, said partitions forming closed connections with the side wall of said last-named chamber at one of their ends, said channels extending in directions crosswise of the arch of said top, inlets for mixed fluid-fuel at one side of the arch of said top arranged to direct the products of combustion solely along the curvature of said arch, passages at the other side of said arch and at the respective end-portions of said heating chamber between said heating chamber and said end channels respectively, the other 115 ends of said partitions terminating in said second-named chamber under said floor at points spaced from the bases of said arch to form passages between said end channels and middle channel at that side of said furnace where said inlets for fluid-fuel are located, said middle channel having an outlet for the products of combustion at that end thereof distanced from said last-named passages.

2. In a fluid-fuel furnace of the character described, a heating chamber provided with an arched top and a floor, inlet passages for mixed fluid-fuel at one side of said arch, mixers for said fluid-fuel at the outer ends 130

of said inlet passages, means for deflecting said mixed fluid fuel along the curvature of said arch, means for adjustably distancing said mixers from said deflecting means, a 5 chamber under the above mentioned floor provided with partitions dividing said chamber into a plurality of channels, the tops of which are formed by said floor, said channels extending in directions crosswise 10 of the above mentioned arch, one of the ends of a portion of said channels having communication with said heating chamber at the side of said arch opposite the said fluid-fuel inlets, said partitions having closed connections 15 with the walls of said second-named chamber at said last-named side of said second-named chamber, and the other ends of said channels having communication with each other under said arch, the products of 20 combustion having movement in the channels separated by said partitions in opposite directions.

3. A furnace of the character described comprising a heating chamber having an 25 arched top and a floor, a chamber under said floor, partitions dividing said last-named chamber into a plurality of channels the tops of which are formed by said floor, said channels extending in directions crosswise 30 of the arch of said top, inlets for mixed fluid-fuel at one side of the arch of said top, said partitions terminating under said arch in rear of said one side of said arch, one of the ends of a portion of said channels 35 having communication with said heating chamber at the side of said arch opposite the said fluid-fuel inlets, and the other ends of said channels having communication 40 around said terminated ends of said partitions with each other, the products of combustion having movement in the chambers

separated by said partitions in opposite directions.

4. In a furnace of the character described, the combination of a heating chamber comprising an arched top and a floor, a chamber under the floor, partitions of less length than the width of said arch connecting at one of their ends with the walls of said second-named chamber, said partitions dividing said last-named chamber into a plurality of channels the tops of which are formed by said floor, said floor having a deflecting end extending in the general direction of curvature of that portion of the 55 arch adjacent thereto and forming a deflecting space under the top level of said floor, said deflecting space extending the length of the said heating chamber at the junction of said floor and arch, the said deflecting end of said floor forming a baffle-wall between said arch and floor, inlets for mixed fluid-fuel at the base of said arch and opposite 60 said baffle-wall, said baffle-wall being adapted to deflect said fluid-fuel along the said arch, one of the ends of a portion of said channels having communication with said heating chamber at the side of said arch opposite the said fluid-fuel inlets, and the 65 other ends of said channels having communication with each other around said partition, whereby the products of combustion in neighboring ones of said channels have movement in opposite directions. 70

In testimony whereof, I have hereunto signed my name in the presence of two subscribing witnesses.

WILLIAM S. RALYA.
